United States Patent Office.

JAMES F. WOOD, 2D, OF COHOCTON, NEW YORK.

Letters Patent No. 70,145, dated October 22, 1867.

IMPROVED CAR-BRAKE.

The Schedule referred to in these Letters Patent and making part of the same,

TO ALL WHOM IT MAY CONCERN:

Be it known that I, JAMES F. WOOD, 2D, of Cohocton, in the county of Steuben, in the State of New York, have invented certain new and useful Improvements in Car-Brakes for street cars, and for other purposes; and the following is a full, clear, and exact description of the same, reference being had to the accompanying drawings making a part of this specification, in which—

Figure 1 represents a section through a side elevation.

Figure 2 shows a plan or top view of the frame, car-wheels, and brakes.

The object of my invention is to apply the most simple, cheap, and effective brake to street cars, and may be used for other cars, or any four-wheeled vehicles.

My invention consists in the application of two right-angled levers, so connected together that they form a knuckle-joint, bearing directly upon the centres of the bars to which the brake-blocks are attached, the levers being operated by rods or chains connected with the cranks, or hand-wheel shafts, on the platforms at both ends of the car.

My invention further consists in the adjustable connecting-links, to regulate the distance of the brake-bars, which effects the pressure of the brakes on the wheels, to compensate for the wear of the blocks. Also, the sliding suspension-rods, to allow the friction of the wheels to tighten the brakes on them.

To enable others to make and use my invention I will describe it more fully, referring to the drawings, and to the letters marked thereon.

To the truck-frame, or bottom of the car A A, are the four car-wheels, B B B B, hung in the usual manner. The brake-blocks C C being secured to the bars D D, are suspended on rods, b b, which have an extended link or slot, c c, so that they will slide up on the hook a a in the frame A A, to which they are attached, so that when the blocks C C bear on the wheels B B they will slide up and tighten the brakes. Through the centre of the bars D D are the adjustable connecting-links d d, they having a screw-nut, e e, on both sides of the bar, so that the joints of the right-angled levers E F may be carried to or from the bars D D, to lengthen or shorten the distance between them, as the brake-blocks C wear off by use, and are easily kept adjusted, the right-angled levers E F being pivoted at their elbows to the connecting-links d d, so that the horizontal parts come together, and are pivoted, forming a knuckle-joint, f, as seen in fig. 1. To the top ends of the vertical part of the levers E F are rods g h, attached, which connect with the cranks I J on the shafts k k at the ends of the platform. If desirable, chains may be used to wind on the shafts of hand-wheels, in the usual manner.

Thus it will be seen that by the action of the knuckle-joint, as constructed and arranged, the power applied to the brakes will be uniform and very great, and easily operated.

What I claim as my invention, and desire to secure by Letters Patent, is—

1. The arrangement of the two right-angled levers, so connected together that they form a knuckle-joint, bearing on the centre of the brake-bars, operating in the manner substantially as and for the purposes herein set forth.

2. I claim the adjustable links d d and the sliding suspension-rods b b, as arranged for the purposes herein described.

Subscribed to on this 13th day of November, 1866.

JAMES F. WOOD, 2D.
